Patented Nov. 21, 1916.

UNITED STATES PATENT OFFICE.

CONRAD HUBERT, OF NEW YORK, N. Y.

PORTABLE ELECTRIC LIGHT.

1,205,633.

Specification of Letters Patent.

Patented Nov. 21, 1916.

Application filed March 6, 1915. Serial No. 12,479.

To all whom it may concern:

Be it known that I, CONRAD HUBERT, a citizen of the United States, residing at the borough of Manhattan, in the county of New York and State of New York, have invented certain new and useful Improvements in Portable Electric Lights, of which the following is a specification, reference being had therein to the accompanying drawings, forming part thereof.

My invention relates to flash lights or portable electric lights suitable for carrying in the hand in use and relates more particularly to that type of these lights known in the trade as electric lanterns.

One of the objects of my invention is to produce an electric lantern which simulates in general appearance a familiar form of oil-burning lantern, and in this connection other objects of my invention are simplicity of construction, inexpensiveness of manufacture, durability, certainty of operation and of maintenance in operable condition, and other more particular objects and advantages which will hereinafter appear.

My invention includes features of construction and combinations of parts as will appear from the following description.

I shall now describe the electric lantern illustrated in the accompanying drawings embodying my invention and shall thereafter point out my invention in claims.

Figure 1 is a central vertical section of the lantern with the lamp and battery in elevation. Fig. 2 is an inverted plan with parts in section. Fig. 3 is a vertical section on a plane indicated by the line 3—3 of Fig. 2 as viewed from above. Fig. 4 is an elevation of the parts of the circuit closer. Fig. 5 is a vertical section of the casing with the bottom closure in elevation at the lower left part of Fig. 1.

The electric lantern embodying my invention illustrated in the accompanying drawings has a sheet metal battery-containing casing 1 of flattened cylindrical shape forming the base of the lantern. A sheet metal battery holding socket or clip 2 is supported in the casing 1 and is insulated therefrom by a paper ring 3 and a wooden disk 4. The battery holder 2 is shown as secured to the lower side of the insulating disk 4 by means of screws 5 and the disk 4 is secured to the top of the casing 1 by screws 6. A battery 8 having the usual outer insulating covering fits closely in and is gripped and

held by the battery holder 2 and the bent-over or inclined contact terminal 9 of the battery 8 forms an electrically conductive connection with the adjacent end of the metal battery holder 2 as appears in Figs. 1 and 2 of the drawings and the other battery terminal 10 is left free or without electrical connections during the open circuit condition of the lantern as appears in Fig. 2. The battery holder 2 is open at the bottom and the lower side of the casing 1 is closed by means of a removable bottom 11, the central portion of which presses upon and assists to hold the battery 8 in place in the battery holder 2. The bottom closure 11 is removably held in place in the casing 1 by means of slight outwardly indented lugs 12 which engage above an inturned rim at the lower edge of the casing 1 as clearly appears in the drawings, a notch 13 being provided in such rim to provide for the attachment or removal for the bottom closure 11. By reason of the insulation of the electrically conductive battery holder 2 from the casing 1, both of the contact terminals 9 and 10 of the battery 8 are insulated from the casing 1 in the open circuit condition of the lantern this being the condition shown in the drawings.

A screw-threaded metal lamp socket 14 has an inner flange as shown resting upon and forming an electrical connection with the outside of the top of the casing 1. The lamp socket 14 is held in place on the casing 1 by a combined retaining screw and contact member 15, the head of the contact screw 15 being within the lamp socket 14 and this screw passing downward through the top of the casing 1 and through the wooden insulating disk 4 and engaging a nut 16 countersunk in the lower side of the wooden disk 4. The apertures for the passage of the contact screw 15 through the bottom of the lamp socket 14 and the top of the casing 1 are sufficiently large that the screw does not come in contact therewith and the head of this screw within the lamp socket is insulated therefrom by means of a small insulating disk or washer 17 and the lower end of the contact screw 15 comes into contact with and forms an electrical connection with the upper side of the battery holder 2, as appears in Fig. 1. An ordinary miniature incandescent lamp 18 is shown as screwed into the lamp socket 14 so that its central contact terminal is in

contact with the head of the contact screw 15 and hence in electrically conductive connection with the spring battery terminal 9 of the battery 8 and the other contact terminal 5 and the lamp 18 is in electrically conductive relation with the casing 1 through the lamp socket 14.

To obtain the closed circuit condition for lighting the lamp 18 manually actuatable 10 circuit closing means are provided for forming an electrically conductive connection between the casing 1 and the terminal 10 of the battery 8. A bodily slidable circuit closer is provided upon the cylindrical or 15 peripheral portion of the casing 1. A circuit closing metal strip has one end portion forming a spring contact finger 19 within the casing 1 and has an oppositely projecting combined guiding and locking end portion 20 at the inside of the casing 1 and has a median outwardly turned U-shaped loop 21 which projects to the outside of the casing 1 through a slotted opening or guide aperture 22 in the casing. A short retaining 25 pin 23 passes through the projecting loop 21 and projects therefrom at each end for holding the circuit closing strip in place on the casing. The retaining pin 23 is held in place in the loop 21 by means of an indentation 30 at the outside of the loop, Fig. 4, forming a corresponding inner projection which enters an annular groove in the retaining pin 23, Figs. 3 and 4. The contact finger 19 is bent inward away from the casing 35 1 at its free end in position to engage the contact terminal 10 of the battery 8 when the slidable circuit closer is moved in a counter-clockwise direction as seen in the inverted view afforded in Fig. 2. The other 40 end portion 20 of the slidable contact strip is provided as shown, with successive indentations adapted to be successively engaged by an inturned projection 24 on the casing 1, Fig. 2, for securely maintaining 45 either the open circuit or the closed circuit condition as desired.

A convex reflector 25 surrounds the lamp socket 14 being shown as rising substantially to the same height as the top of the lamp 50 socket. The top of the casing 1 is provided with an upwardly projecting screw-threaded globe-supporting flange 26 which is shown as having an annular flat inner portion secured as by soldering to the top of the casing 1. The reflector 25 is shown as provided 55 with a flat marginal or peripheral flange fitting within the globe-supporting casing flange 26 and the reflector 25 is firmly held in place by a lantern globe 27 screwed into 60 the casing flange 26 down upon the peripheral flange of the reflector 25. The lantern may be readily carried about by means of a bail 28 which engages a cap 29 shown as screw-threaded over the top of the chimney, or globe 27.

It is obvious that various modifications may be made in the construction shown in the drawings and above particularly described within the principle and scope of my invention.

I claim:

1. A portable electric light comprising an electrically conductive battery-containing casing, an electrically conductive battery holder in the casing in electrically conductive connection with one of the battery contact terminals and insulated from the casing and supporting the battery with both of its contact terminals out of electrical connection with the casing, an electrically conductive lamp socket carried by the casing and electrically connecting one terminal of the lamp to the casing and supporting the lamp with its other terminal in electrical connection with the battery holder, and a circuit closer for electrically conductively connecting the casing with the battery contact terminal which is not in electrical connection with the battery holder.

2. A portable electric light comprising an electrically conductive battery-containing casing, an electrically conductive battery holder in the casing in electrically conductive connection with one of the battery contact terminals, insulating means supporting the battery holder in the casing with both contact terminals of the battery out of electrical connection with the casing, an electrically conductive lamp socket carried by the casing and electrically connecting one terminal of the lamp to the casing, means forming an electrically conductive connection between the battery holder and the other terminal of the lamp, and a circuit closer for electrically connecting the casing with the battery contact terminal which is not in electrical connection with the battery holder.

3. A portable electric light comprising an electrically conductive battery-containing casing, an electrically conductive battery holder in the casing in electrically conductive connection with one of the battery contact terminals, insulating means supporting the battery holder in the casing with both contact terminals of the battery out of electrical connection with the casing, an electrically conductive lamp socket in contact with the outside of the casing, an electrically conductive combined contact-making and socket-holding member holding the lamp socket in place on the casing, such member being in contact at its inner end with the battery holder and at its outer end being exposed at the center of the bottom of the lamp socket in position to make electrical connection with the center terminal of the lamp, insulation interposed between such holding member and the lamp socket, such member also being out of electrical connection with the casing.

connection with the casing, and a circuit closer for electrically connecting the casing with the battery contact terminal which is not in electrical connection with the battery holder.

4. A portable electric light having, in combination, a sheet metal battery-containing casing of flattened cylindrical shape forming the base of the light and open at its lower flat side, a sheet metal battery-holding socket secured to the upper side of the casing and open at its lower side adjacent to the open lower side of the casing for inserting or removing the battery through the open side of the socket and casing, and a resilient sheet metal closure for the open lower side of the casing offset inwardly at the middle yieldingly to press upon and hold the battery in the socket, the

closure and casing being provided with interengaging means for locking the closure in closed battery-retaining position on the casing.

5. A portable electric light having, in combination, a battery-containing casing, a lamp socket projecting from the outside of the casing, a convex reflector surrounding the lamp socket, a globe-supporting flange on the casing surrounding the reflector, and a chimney globe held by such flange and holding the reflector in place on the casing.

In testimony whereof I have affixed my signature in presence of two witnesses.

CONRAD HUBERT.
